UNITED STATES PATENT OFFICE.

FREDERIC M. SIMONS, OF SWARTHMORE, PENNSYLVANIA, ASSIGNOR TO FREDERIC M. SIMONS, OF SAME PLACE, JOHN F. SIMONS AND THOMAS MADDOCK, OF PHILADELPHIA, PENNSYLVANIA, AND EDWARD S. SIMONS, OF ORANGE, NEW JERSEY.

DESIGN FOR A BELT.

SPECIFICATION forming part of Design No. 29,489, dated October 18, 1898.

Application filed April 15, 1898. Serial No. 677,749. Term of patent 3½ years.

To all whom it may concern:

Be it known that I, FREDERIC M. SIMONS, of Swarthmore, Delaware county, Pennsylvania, have invented and produced a new and original Design for Belts, of which the following is a specification.

My design for belts is shown in the accompanying drawings, in which—

Figure 1 is a perspective view of a belt embodying my design, and Fig. 2 is a transverse vertical sectional view of the same.

The belt is longitudinal in shape, having a loose puffed outer face A, confined by transverse bands B, forming a series of longitudinal puffed portions separated by the intermediate transverse bands and having the lon-

gitudinal creases extending therefrom. The face of the belt is thus composed of a series of longitudinal puffed portions gathered at their ends, where they are separated from one another by intermediate transverse bands.

Having now described my design, what I claim as new, and desire to secure by Letters Patent, is—

The design for a belt substantially as herein described and shown.

In testimony of which invention I hereunto set my hand.

FRED. M. SIMONS.
